Application filed March 20, 1893. Serial No. 466,946. Term of patent 7 years.

To all whom it may concern:

Be it known that I DE VER H. WARNER, a citizen of the United States, residing at Bridgeport, Fairfield county, State of Connecticut, 5 have invented a certain new and useful Design for a Dress-Stay, of which the following is a specification.

My invention is a design for a dress stay, embodying the features hereinafter more particularly pointed out.

In the accompanying drawing, I have shown a perspective view of a dress stay embodying my design.

The design embodies a stay A, having a longitudinal, flat, central portion a, and the sides or edges b are of irregular contour, being shown substantially tooth-shaped, and extending substantially the length of the stay. Upon the upper surfaces, two parallel strips rounded in cross-section are placed, respectively lying near the irregular edges of the stay, and projecting above the level of the flat portion. 20

The essential features of the design consist in a stay having a central flat portion, irregular or serrated edges and parallel strips rounded in cross-section, lying near the edges of the stay. 25

What I claim is—

The design for a dress stay, substantially 30 as herein shown and described.

In testimony whereof I have signed my name to this specification in the presence of two subscribing witnesses.
